UNITED STATES PATENT OFFICE.

JOHN HRITE, JR., AND STEPHEN SIVICK, OF HASTINGS-UPON-HUDSON, NEW YORK.

NAIL-HOLDING ATTACHMENT FOR HAMMERS.

1,247,683.

Specification of Letters Patent. Patented Nov. 27, 1917.

Application filed October 25, 1916. Serial No. 127,584.

To all whom it may concern:

Be it known that we, JOHN HRITE, Jr., and STEPHEN SIVICK, citizens of the United States, residing at Hastings-upon-Hudson, in the county of Westchester and State of New York, have invented certain new and useful Improvements in Nail-Holding Attachments for Hammers, of which the following is a specification.

10 This invention relates to certain new and useful improvements in nail holding attachments for hammers.

The primary object of the invention is to provide an improved form of nail holding attachment for hammers in which the attachment therefor being in the form of a forked element is detachably associated with the hammer head with the outer face thereof lying within the plane of the outer

20 face of the hammer. A further object of the invention is to provide a nail holding attachment for hammer heads, in which the attachment is in the form of a forked element that is entirely fastened to the hammer head on one of its exposed sides, the forked element being substantially wedge-shaped for reception in a similarly shaped socket in the hammer head whereby the same may be effectively retained in position.

With the above general objects in view and others that will appear as the nature of the invention is better understood, the same consists in the novel construction, combination and arrangement of parts to be hereinafter more fully described and then claimed.

In the accompanying drawing forming a part of this application and to which reference is had herein by like characters designating corresponding parts throughout the several views:

Figure 1 is a side elevational view of a hammer head with the present form of nail holding device attached thereto.

Fig. 2 is an end elevational view thereof showing the dove-tailed connection between the nail holding element and the hammer head.

Fig. 3 is a longitudinal sectional view taken on line III—III of Fig. 1.

Fig. 4 is a detail perspective view of the nail holding device detached from the hammer head.

Fig. 5 is a side elevational view of a

hammer head with the modified form of nail holding device secured thereto.

Fig. 6 is a longitudinal sectional view on line VI—VI of Fig. 5, and

Fig. 7 is a detail perspective view of the modified form of nail holding device detached from the hammer head.

The present invention aims to provide a nail holding attachment for hammer heads, in which the nail holder is alone associated with one of the outer side faces of a hammer head and so positioned in a socket or recess in the hammer head as to have the main portion thereof lying within the outer side of the hammer. Two forms of the invention are shown, the preferred form including a dove-tailed interlocking connection between the nail holder and hammer head as shown in Figs. 1 to 4 with a fastening device as a screw, for retaining the same in position while a modified form of the device is shown in Figs. 5 to 7 and includes a flat plate received in a similarly shaped recess in the outer side of a hammer head with a fastening device as a rivet for permanently securing the same in position.

Referring more in detail to the accompanying drawing, the reference numeral 10 designates the body portion of a hammer head having the usual hammering end head 11 and the nail extracting jaws 12. One side face of the hammer head 10 has a wedge-shaped socket or depression 13 formed therein with the smaller end thereof positioned at the outer end of the hammer 10. The outer end of the recess 13 is provided with a dove-tailed seat 14 as more clearly shown in Figs. 2 and 3.

The preferred form of the nail holding device 15 associated with the hammer head 95 includes a pair of prongs 16 angularly disposed coincident to the side walls of the socket 13 with the free ends thereof slightly turned outwardly as at 17 to be spaced from the outer face of the hammer head 10. A 100 dove-tail block projection 18 is carried by the nail holder 15 and is adapted to be slidably received in the dove-tailed seat 14 in the hammer head 10 to be assembled as shown in Figs. 1 to 3. When in this position, a fastening screw 19 passes through an opening 20 in the nail holder 15 and is threaded into the hammer head 10 as clearly shown in Figs. 2 and 3. In this position the block 18 and legs 16 lie within the dove-

- 2
- tailed seat and recess 13 so that the only projecting parts of the nail holding device are the outwardly projecting ends 17 as clearly indicated in Fig. 3. In this position the desired resiliency is placed upon the legs 16 so that a nail head gripped between the same and the hammer head will be effectively retained thereby for the purpose desired.
- 10 A modified form of the device is shown in Figs. 5 to 7 and in this construction, a recess 13 of wedge-shape is alone provided with the exclusion of the dove-tailed seat 14, while the nail holding element is free of the block projection 18. As shown in Fig. 6, a suitable fastening means, as a rivet 21, passes through the opening 20 in the nail holder 15 and through a corresponding opening in the hammer head 10 and is retained therein by swaging the inner end of the rivet in the usual manner. In this construction, the nail holding element is also positioned inwardly of the outer face of the hammer head with the curved end 17 alone projecting therefrom while the particular form of wedge slot and nail holder effectively retains the same in position against outward movement of the nail holder relative to the hammer head.
- 20 While the form of the invention herein shown and described is what is believed to be the preferable embodiment thereof, it is nevertheless to be understood that minor changes may be made in the form, proportion and details of construction without departing from the spirit and scope of the invention as hereinafter claimed.
- 30
- 35

What is claimed as new is:—

1. A nail placer comprising a head having a recess in one face thereof, the side walls 40 of said recess being longitudinally converging, and a substantially flat nail-engaging element rigidly secured to said head at the narrow end of the recess and lying normally within the plane of the said face, said element being of a form whereby its side edges substantially contact with the converging side walls of the recess throughout their length and being provided with a substantially V-shaped elongated longitudinal 45 notch inwardly from its wider end producing a pair of symmetrical diverging springy nail-engaging fingers to clamp the head of a nail between the under faces thereof and the bottom wall of said recess. 55

2. A nail driving implement having a transverse groove in one face thereof, said groove having straight longitudinally converging unobstructed side walls, and a substantially V-shaped flat nail holding element 60 fitted in said groove normally within the plane of said face of the implement and contacting with the bottom wall of said groove substantially throughout its entire length, the free ends only of the nail holding element being slightly outwardly deflected, and means to secure the narrow end of said nail holding element to said implement against outward and endwise displacement from the groove. 65

In testimony whereof we affix our signatures.

JOHN HRITZ, JR.
STEPHEN SIVICK.
